UNITED STATES PATENT OFFICE.

EUGENE F. JONES, OF RICHMOND, VIRGINIA, ASSIGNOR OF ONE-HALF TO F. A. SPENCE,
OF RICHMOND, VIRGINIA.

COVER-FASTENER.

1,073,136.

Specification of Letters Patent. Patented Sept. 16, 1913.

Application filed October 14, 1912. Serial No. 725,699.

To all whom it may concern:

Be it known that I, EUGENE F. JONES, a citizen of the United States, residing at Richmond, in the county of Henrico and 5 State of Virginia, have invented certain new and useful Improvements in Cover-Fasteners; and I do declare the following to be a full, clear, and exact description of the invention, such as will enable others skilled in 10 the art to which it appertains to make and use the same.

This invention relates to improvements in box or cover fasteners and is especially adapted for use in securing the tops and bottoms 15 of knockdown boxes detachably in position.

The object of the invention is to provide a simply constructed, cheap and efficient device of this character which may be quickly 20 applied and which will reliably hold the cover in engagement with the article upon which it is mounted.

With this and other objects in view, the invention consists of certain novel features 25 of construction, and the combination and arrangement of parts as will be more fully described and claimed.

In the accompanying drawings: Figure 1 represents a perspective view of a box 30 equipped with this improved cover fastener; Fig. 2 is an end elevation with parts broken out showing one of the cover fasteners in operative position and the other in released or disengaged position; Fig. 3 is an enlarged 35 sectional detail taken on the line 3—3 of Fig. 2; Fig. 4 is a perspective view of the fastener detached.

In the embodiment illustrated a knock-down box 1 is shown having a removable 40 top 2 and bottom 3 secured in position by this improved fastener which is here shown in the form of a substantially L-shaped member 4, the short arm 5 of which is inclined to facilitate its locking engagement 45 with a notch 6 formed in the side member of the box. The notches 6 here shown are formed in cleats 7 and 8 secured to the side walls of the box to which the top and bot-

tom are secured by these improved fasteners. The outer walls of these notches 6 are 50 inclined inwardly as shown at 9 with which the hook shaped or inclined arm 5 of the fastener is designed to engage when swung inwardly in the position shown at the left of Fig. 2 and in which position it is held 55 by a pin 10 extending transversely behind said catch 4. Four of these fasteners 4 are shown for securing the top 2 in position and the shanks or long arms thereof extend through and are pivoted in openings 11 in 60 the top, said openings being beveled at their opposite ends to permit the swinging motion of the upper ends of the fasteners. The hook shaped lower ends of the fasteners extend into recesses 12 formed in the upper 65 ends of cleats 13 and 14 secured to the outer face of the end members of the box to which the cover is applied and to lock said cover in position the lower hook shaped ends of the fasteners are swung inwardly into engagement 70 with the notches 6 and are then secured in this position by the pins 10 above referred to. To disengage the catches or fasteners 4 when it is desired to remove the top of the box the pins are withdrawn and the upper ends of the catches actuated to 75 swing their inner ends out of engagement with the notches 6 and the top may then be freely removed. While I have described the top only as secured by these fasteners it is 80 obvious that the bottom 3 may be secured in the same manner and it is so shown in dotted lines in Fig. 2 of the drawings.

While I have described my invention with more or less minuteness as regards details 85 and as being embodied in certain precise forms, I do not desire to be limited thereto unduly any more than is pointed out in the claim. On the contrary, I contemplate all proper changes in form, construction and arrangement, the omission of immaterial elements and substitution of equivalents as circumstances may suggest or render expedient. 90

I claim as my invention:

The combination with a receptacle having 95 a recess in the upper edge of one wall with

a notch extending laterally from said recess and provided with an upwardly inclined upper wall, of a cover having a latch pivotally mounted thereon and provided at its lower end with an upwardly inclined hook adapted to engage the inclined wall of the notch in said receptacle.

In testimony whereof I have hereunto set my hand in presence of two subscribing witnesses.

EUGENE F. JONES.
